CLAIM

The ornamental design for the upholstery design for an examination chair, as shown and described.

DESCRIPTION

FIG. 1 is a front perspective view of an upholstery design for an examination chair that shows our new, original and ornamental design.

FIG. 2 is a front view of the upholstery design for an examination chair of FIG. 1.

FIG. 3 is a back view of the upholstery design for an examination chair of FIG. 1.

FIG. 4 is a left side view of the upholstery design for an examination chair of FIG. 1.

FIG. 5 is a right side view of the upholstery design for an examination chair of FIG. 1.

FIG. 6 is a bottom view of the upholstery design for an examination chair of FIG. 1; and,

FIG. 7 is a top view of the upholstery design for an examination chair of FIG. 1.

The broken lines in the drawings depict portions of an examination chair that form no part of the claim design.
